DESIGN.

F. MANKEY.

MOLDING.

No. 17,182.

Patented Mar. 15, 1887.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 17,182, dated March 15, 1887.

Application filed July 1, 1886. Serial No. 206,873. Term of patent 7 years.

To all whom it may concern:

Be it known that I, FREDERICK MANKEY, of Williamsport, Lycoming county, Pennsylvania, have invented and produced a new and original Design for Ornamental Trims or Moldings, of which the following is a specification, reference being had to the accompanying photograph, forming part hereof.

My design relates to an ornamental trim or molding in the form of a band or bar; and it consists in the configuration thereof, substantially as represented.

On one edge of the bar appears a series of concave indentations, A, separated by straight portions B. On the other edge appears a set of three scallops, D E F, grouped so that the middle scallop, E, projects beyond the adjacent scallops D F. These groups of scallops are disposed along the edge of the bar and are separated by straight portions G. On the face of the bar are circular indentations, as H. Diverging from the vicinity of each of said indentations are straight channels or grooves I J K L, which terminate at the points of junction of the scallops D E F. Instead of making the circular depression a simple concave depression, as H, I may make it an annular depression, as M. I may also substitute for the four straight grooves, I J K L, three lenticular depressions, N O P, which diverge from the circular depression and have their ends opposite the middle portions of the scallops D E F.

In the accompanying photograph I show a set of scallops D E F, and on the proximate face of the bar an annular depression, M, and lenticular depressions N O P, then another set of scallops D E F, and on the proximate face to these a circular concave depression, H, and straight diverging channels I J K L, and so on alternating along the band. Also, on the face of the band, and opposite the middle points of the straight portions D, I show annular recesses Q.

The recesses Q may be omitted. If desired, on the face proximate to every group of scallops may appear the depressions H and the straight channels I J K L, or the depression H and the lenticular depressions N O P, or the depression M and the channels I J K L, or the depression M and the depressions N O P.

I claim—

The design for an ornamental trim or molding, substantially as herein shown and described, which consists in the concave indentations A and the straight portions B on one edge, and on the opposite edge the groups of scallops D E F, and on the face of said bar a circular cavity, as H or M, and depressions radial to the center thereof.

FREDERICK MANKEY.
